CLAIM

The ornamental design for an electronic locker lock, as shown and described.

DESCRIPTION

FIG. 1 is a front, left perspective view of an electronic locker lock, showing my new design;

FIG. 2 is a top plan view thereof;

FIG. 3 is a left side elevation view thereof;

FIG. 4 is a front elevation view thereof;

FIG. 5 is a right side elevation view thereof; and,

FIG. 6 is a bottom plan view thereof.

Features shown in dashed lines are not part of the claimed design.
